No. 610,789.

Patented Sept. 13, 1898.

E. A. BEACH.
COLANDER.

(Application filed Jan. 22, 1898.)

(No Model.)

UNITED STATES PATENT OFFICE.

EDWARD A. BEACH, OF ALTOONA, PENNSYLVANIA.

COLANDER.

SPECIFICATION forming part of Letters Patent No. 610,789, dated September 13, 1898.

Application filed January 22, 1898. Serial No. 687,596. (No model.)

To all whom it may concern:

Be it known that I, EDWARD A. BEACH, a citizen of the United States, residing at Altoona, in the county of Blair, State of Pennsylvania, have invented certain new and useful Improvements in Colanders, of which the following is a specification, reference being had therein to the accompanying drawings.

This invention relates to colanders, and is particularly designed for culinary uses, such as the straining of fruits or vegetables to separate the seeds from other portions thereof, and is also intended for use as a fruit-washer.

15 The invention has for its object to provide a construction of parts by which the sieve or screen can be readily detached and a different one substituted therefor and in which the stirrer is easily removed when convenient or necessary.

20 Other objects and advantages of the invention will hereinafter appear in the following description, and the novel features thereof will be particularly pointed out in the appended claims.

25 In the drawings, Figure 1 is a perspective of the invention with the sieve separated from the body thereof. Fig. 2 is vertical section, with parts broken away, illustrating the members assembled in position for use; and Fig. 3 is a partial horizontal section at the upper portion of the blades.

Like letters of reference indicate like parts throughout the several figures of the drawings.

35 The letter A indicates the body portion of a colander, which is provided with a circumferential bead A'. The lower portion of the body has thereon oppositely-located lugs or pins A², which operate in connection with bayonet-slots B', provided in the upper band B³ of the sieve or screen B. The bayonet-slots B' extend in opposite directions, so that the band B³ is brought into contact with the bead A' and slightly rotated. The pins A² will travel in the horizontal portions of the slots and thus securely fasten the sieve to the body portion of the colander. If desired, suitable handles B⁵ may be located opposite each bayonet-slot B', which form a convenient method of handling the sieve and also strengthen the band B³ at the portion where

the slots are cut therein. The extreme lower portion of the sieve or screen B is provided with a solid tip B⁴, which prevents injury to 55 the screen and forms a bearing for the lower portion of the stirrer C, which operates with- in the same. It may be stated that various forms and characters of reticulated material may be used to form the sieve or screen, the 60 same being governed by the character of ma- terial for which the colander is designed. In fact several different sizes of screens may be furnished with each colander and the same replaced or removed as desired in use. 65

The stirrer C is provided at its lower por- 70 tion with bifurcated arms C', from each of which extends a skeleton frame C² to form blades. These blades do not come in contact with the walls of the sieve, but are removed 75 in a slight distance therefrom, as indicated in Fig. 3. Between the arms C' a block C³ of wood or other suitable material is located, which is substantially V-shaped and travels in close proximity to the surface of the sieve. 75 The lower portion or apex C⁴ of this block extends below the ends of the arm C' and forms a bearing for the stirrer. The block is also provided centrally at its upper por- 80 tion with a recess or seat C⁵, adapted to en- compass the crown of the bifurcated arms, and thus hold the block against movement between said arms. It is obvious that other holding means may be used, if found desirable or necessary. 85

The upper portion of the stirrer is sup- 90 ported in a vertical position by means of a supporting-arm D, which extends upwardly and inwardly from the side of the body and is provided at its outer portion with a handle D' for use in supporting the colander. This handle is suitably secured to the side of the body, and the inner end of the arm D is pro- 95 vided with a recess D² of substantially the diameter of the circular portion d of the stir- rer C and with a slot D³, leading into said recess and of less diameter than the recess. The slot D³ is of substantially the diameter of the lower flattened portion d' of the stirrer C, whereby this portion may be introduced 100 into the slot and the stirrer then moved down- ward, so that the circular portion d thereof rests within the recess and cannot be re- moved therefrom by lateral movement when

the parts are in position for use. To remove the stirrer, the same is lifted upward until the portion d' comes into alinement with the slot D^3 , when by a lateral movement the stirrer can be removed from the supporting-arm. The upper portion of the stirrer is provided with a suitable operating arm or handle C^5 .

- The operation of the several parts will be apparent from the foregoing description, from 10 which it will be seen that the novel construction of stirrer permits the ready removal of the same and at the same time secures the stirrer against any lateral movement when in position for use. The application of the block 15 of wood or other non-metallic material prevents the contact of the metallic blades with the sieve. The bearing for the stirrer is also obtained upon a wooden surface, so that all friction between adjacent metallic parts is 20 prevented and the life of the reticulated surface thereby greatly lengthened and the efficiency of the colander increased. The removable sieve permits the use of different characters of screens, which when attached 25 to the body of the colander are firmly held in contact therewith.

The colander is particularly adapted for straining fruits and vegetables to remove therefrom solid portions, such as seeds, and is 30 also capable of use as a mixer for the purpose of mixing and straining different characters of material. When used as a washer for fruit or vegetables, the lower portion of the same is submerged, so that the handles B^3 rest upon 35 the top of the vessel containing the water, and the movement of the stirrer thoroughly washes the fruit or vegetables, which will be drained when the colander is lifted out of the water.

- 40 It is obvious that changes may be made in the details of construction and also in the configuration of the several parts without departing from the spirit of this invention, as defined by the appended claims.

Having described my invention and set 45 forth its merits, what I claim as new, and desire to secure by Letters Patent, is—

1. A colander comprising a body portion provided with lugs at its lower portion, a conical sieve formed with a band at its upper portion having therein bayonet-slots, a stirrer formed with tapering blades adapted to lie within said sieve and having a bearing at the apex thereof, and a handle secured to the casting and having therein an upwardly and inwardly extending arm provided with a slotted recess to receive and removably retain the upper portion of said stirrer; substantially as specified. 50

2. A colander comprising a body portion, a 60 detachable sieve secured thereto, a stirrer provided at its lower portion with bifurcated arms and skeleton blades extending therefrom, and a non-metallic block located between said arms and extending at substantially right angles to said blades; substantially as specified. 65

3. A colander comprising a body portion provided with a circumferential bead and oppositely-located lugs, a conical sieve having 70 a band at its upper portion formed with oppositely-extending bayonet-slots, an upwardly and inwardly extending arm provided with a circular recess and an angular slot leading into the same, a stirrer formed at its lower 75 portion with bifurcated arms carrying skeleton blades, a block located between said arms, an upwardly-extending shank from said arms provided with circular and angular portions, and an operating-handle located at the upper 80 end of said shank; substantially as specified.

In testimony whereof I affix my signature in presence of two witnesses.

EDWARD A. BEACH.
